UNITED STATES PATENT OFFICE.

PHILIP KEMPTER, OF MILWAUKEE, WISCONSIN, ASSIGNOR TO GEUDER, PAESCHKE & FREY CO., OF MILWAUKEE, WISCONSIN, A CORPORATION OF WISCONSIN.

SHIPPING-CASE FOR FILMS AND THE LIKE.

1,314,269.

Specification of Letters Patent. Patented Aug. 26, 1919.

Application filed April 1, 1919. Serial No. 286,650.

To all whom it may concern:

Be it known that I, PHILIP KEMPTER, a citizen of the United States, residing in Milwaukee, county of Milwaukee, and State of Wisconsin, have invented certain new and useful Improvements in Shipping-Cases for Films and the like, of which the following is a full, clear, and exact description thereof.

My invention relates to shipping cases for films and the like. Such cases may be used for shipping any fragile material which requires a strong, light-weight container.

I have as an object of this invention the provision of such a shipping case which may be constructed entirely of metal, preferably sheet metal, which will stand service without rapid deterioration.

I have provided a case which is of such configuration and outline that a plurality of such cases may be readily stacked in any way that is convenient without having exposed parts which would cause interference. The case is light in weight and entirely fire-proof. It can be carried about readily by bringing a handle into proper position.

Other objects will be apparent as the description proceeds, and I will have it understood that my invention is not to be limited to the showing in the drawings, but rather to the scope of the claims which follow the description.

In the embodiment shown in the drawings,

Figure 1 is a perspective view of a shipping case with the cover closed;

Fig. 2 is a section through the cover and the front wall of the case showing the cover closed, and the means for retaining it closed;

Fig. 3 is a section through the cover and one of the hinges with the cover closed and showing in dot and dash the cover in the open position; and

Fig. 4 is a plan view of the sliding bolt used to lock or retain the cover closed.

Like reference characters relate to like parts throughout the several views.

In the form shown, the case is substantially rectangular in configuration and slightly wider than deep. It has side walls 5 which are made up of a single piece of sheet metal which has been folded back upon itself, as at 6 in Fig. 3, and is provided with a stiffening wire 7, the sheet being

folded or rolled about such wire at its edge, as at 8. The body portion of the side walls 5 is corrugated in any desirable manner to provide stiffness. As shown, these corrugations comprise three parallel ribs 9. These corrugations do not extend all the way around the walls, but are discontinued in 60 the front portion of one wall to provide space for pasting a label, as at 10. The strip from which the side walls 5 is made is preferably lap welded at the back side of the case.

A bottom 11 of sheet metal is bent to the form shown in Fig. 3 at 12, and envelops the lower edge of the side wall member 5. The bottom 11 and the lower edge of the side wall 5 are preferably spot welded at 13, as 70 this will not affect the metal by destroying its temper. Any other suitable means, however, may be used for fastening these parts together.

In order that the top of the shipping case 75 may present a smooth surface, so that cases may be stacked on top of one another, suitable depressions are provided to receive hinges, handle and retaining device.

The cover 20, which is generally of rectangular configuration, has a depending rim 21 which is adapted to closely encircle the upper edge of the side wall member 5 outside of the doubled over portion 6. The cover is provided centrally with a depression 22 which extends forward, as at 23, to the surface of the front edge of the rim 21, where the rim is not so wide, as clearly shown in Fig. 1. In this depression I have mounted a suitable bail-like handle 24 which 90 is carried on a strap 25 secured by suitable rivets at 26. The forward depressed portion 23 carries, by suitable rivets 26', two U-shaped strap members 27 and 28. These members 27 and 28 coöperate with the upper surface of the depressed portion 23 of the cover to slidingly guide a bolt or retaining member 29, which, in Figs. 1 and 2, is shown in a position to hold the cover closed.

A suitable leaf spring, as 30, is fastened 100 to the bolt 29 and slides underneath strap member 28, and the bolt 29 is provided intermediate its ends on the under side with a slot 31 which is adapted to coöperate with the head of a rivet 32 to limit the motion of 105 the bolt. A suitable enlargement 33 at the

inner end of the bolt serves for gripping the same to slide it.

Fastened to the inner surface of the side walls 5 at the front of the case is an upright member 34 which is adapted to pass through a hole 35 in the depressed portion 23 of the cover 20. The upper end 36 of the upright member 34 is provided with a hole 37 in alignment with the sliding bolt 29 and 10 through which this bolt is adapted to be passed when it is desired to retain the cover in closed position. To provide means for sealing the case, so that tampering may be prevented, a small hole 38 is provided on the 15 outer end of the bolt 29. Any suitable sealing wire may be passed through this hole.

As shown in Fig. 4, the bolt 29 on its outer end has a shoulder 30' which abuts against the upper end 36 of the member 34, 20 and this definitely limits the outward movement of the sliding bolt 29.

By reference to Fig. 3, wherein I have shown the improved hinge for use on the receptacle, it will be seen that the cover member 20 has been depressed as at 40 to provide a space in which one part 41 of the hinge may be suitably fastened as by rivets 42. The free end of this part of the hinge is rolled or folded upon itself as at 43 to 30 provide an eye. The back side wall 5 carries riveted thereto a fixed member 44 which is also provided with an eye 45. A suitable link 46 is fastened in these eyes. A cover has been shown in open position in dot and 35 dash lines, and it will be clear that in such position it has been entirely freed from the top of the receptacle and is out of the way when access to the receptacle is desired.

After the metal parts above enumerated 40 have been assembled, the entire device is subjected to a galvanizing process, whereby all parts are covered with a protective layer of zinc, so that corrosion is prevented and in order to give a finished appearance to the 45 case.

The inside of the case is lined with a suitable material as fiber. This material is shown as made of three pieces, one part 50 being close to the inside of the side walls 5. 50 The other part of this lining 51 is carried by the bottom 11, and the third part 52 is carried by the cover 20. Any suitable means may be used for holding this lining in place, whereby the lining may be readily removed 55 and replaced.

While I have shown and described as an embodiment of my invention a shipping case of right prismatic configuration, peculiarly adapted for the accommodation of reels of 60 films, I desire to have it distinctly understood that it is within the province of my invention to construct the case otherwise, as, for example, cylindrical frusto-conical or frusto-pyramidal, in order to adapt the case 65 for protecting articles of other configura-

tions, and the drawings should therefore be considered as illustrative, and not as limiting the invention.

I claim:

1. A sheet metal cover for a receptacle having a portion thereof depressed to receive a hinge member and another portion thereof depressed to receive a handle and a retaining device, said depressed portions extending completely to the edge of the cover. 70 75

2. A sheet metal stamping for the cover of a receptacle, said stamping having a continuous rim pressed therefrom; a depression pressed in the body portion of the stamping and near the rim for a hinge member, and a second depression in the body portion provided with a hole for receiving a receptacle carried member, said second depression providing space to house a retaining device adapted to coöperate with the 80 85 said member.

3. A cover for a receptacle comprising a sheet metal stamping having one portion thereof depressed to receive a hinge member, a hinge member fixed to said stamping in 90 95 said depression, a second depression to receive a handle, a sliding bolt and retaining means therefor, and a handle and a sliding bolt with its associated retaining means in said second depression.

4. A cover for a receptacle comprising a sheet metal stamping having one portion thereof depressed to receive a hinge member, a hinge member fixed to said stamping in said depression, a second depression to receive a handle, a sliding bolt and retaining means therefor, a handle and a sliding bolt with its associated retaining means in 100 105 said second depression, and means to limit the sliding of said bolt.

5. A shipping case having sheet metal walls, a sheet metal bottom, and a sheet metal cover hinged to the walls, said walls being corrugated for strength, the bottom being welded to the walls, said cover carrying a handle and means for retaining the cover closed, the cover being depressed to house said handle and retaining means whereby a smooth surface is presented. 110

6. A shipping case comprising an all metal outside which includes side walls, cover and bottom, the bottom welded to the walls and the cover carrying sealing and retaining means whereby access to the interior may be prevented, and a fireproof lining for the all 115 120 metal part.

7. A shipping case having on the "top" thereof a hinged and sealable cover within the upper surface of which is provided space for externally housing a hinge and a sealing device, and a hinge and a sealing device mounted in such space whereby the cases may be securely stacked on top of one another. 125

8. A shipping case of non-cylindrical con- 130

figuration, said case having a hinged and sealable cover within the upper surface of which is provided space for externally housing a hinge and a sealing device, and a hinge 5 and a sealing device mounted in such space whereby the cases may be securely stacked in any fashion.

9. A shipping case comprising a bottom generally rectangular in configuration, a 10 cover generally rectangular in configuration, side walls intermediate said bottom and said cover, all such parts being of sheet metal, the bottom welded to the walls and the cover hinged to the walls, said cover completely 15 surrounding the upper edge of the walls and having its upper surface depressed centrally and provided with a hole adjacent the edge of the cover, a fixed member carried by said walls and adapted to pass through the hole 35 in the cover, said member having an opening therein in the portion thereof above said cover, and means comprising a slideable bolt carried in the depressed part of the cover for fastening the same closed by being passed 40 through the opening in said member.

10. A shipping case comprising a bottom 25 generally rectangular in configuration, a cover generally rectangular in configuration, side walls intermediate said bottom and said

cover, all such parts being of sheet metal, the bottom welded to the walls and the cover hinged to the walls, said cover completely 30 surrounding the upper edge of the walls and having its upper surface depressed centrally and provided with a hole adjacent the edge of the cover, a fixed member carried by said walls and adapted to pass through the hole 35 in the cover, said member having an opening therein in the portion thereof above said cover, and means comprising a slideable bolt carried in the depressed part of the cover for fastening the same closed by being passed 40 through the opening in said member.

11. In combination, a receptacle, a sheet metal cover therefor and a hinge therebetween, said cover being depressed to receive one part of said hinge whereby a smooth surface is presented, said part being rolled upon itself on the free end, a second part of the hinge being fastened to the receptacle and rolled upon itself at its free end, and a link 45 passed through both said rolled portions 50 whereby the cover may swing clear of the top of the receptacle.

PHILIP KEMPTER.
